UNITED STATES PATENT OFFICE.

HOWARD C. CURTISS, OF NORWOOD, OHIO, ASSIGNOR TO THE AMERICAN LAUNDRY MACHINERY COMPANY, OF CINCINNATI, OHIO, A CORPORATION OF OHIO.

DOOR-CLOSING MECHANISM FOR DRY-CLEANING WASHING MACHINES.

Application filed May 31, 1923. Serial No. 642,505.

This invention relates to improvements in mechanism for automatically closing doors of machines in case of fire, such as doors of washing machines used for cleaning garments with gasoline.

One object of this invention is to provide improved safety mechanism of this character which includes a fusible link or other heat responsive device, which, when subjected to a pre-determined amount of heat, automatically effects the closing of a machine door.

A further object of the invention is to provide safety mechanism of this character which also effects the closing of a machine damper when the heat responsive member of said mechanism is subjected to a pre-determined amount of heat.

Other objects of the invention will appear from the following description and claims when considered together with the drawings.

Fig. 1 is an end elevation of a washing machine embodying my present device; Fig. 2 is a perspective view of the fusible link; Fig. 3 is a broken sectional view of the door closing mechanism taken on line 3—3 of Fig. 4; Fig. 4 is a sectional view taken on line 4—4 of Fig. 3; Fig. 5 is a sectional view similar to Fig. 4 showing the position of the door closing mechanism upon melting of the fuse; Fig. 6 is a sectional view of the flue taken on the line 6—6, of Fig. 7; Fig. 7 is a detail sectional view on the line 7—7 of Figs. 1 and 6; and Fig. 8 is a detail view similar to Fig. 7 and showing the damper in closed position.

The type of washing machine to which my present invention is applied for purposes of illustration is familiar to one skilled in the art and comprises the outer casing 1 in which is rotatably mounted the drum 2, suitable operating mechanism for the drum being indicated at 3. The casing is provided with a door 4 hinged at the point 5 for the purpose of closing an opening in the casing wall to permit access to the interior thereof. The rests 6 are mounted upon the outside of the casing and serve to support the door 4 in open position as indicated in Fig. 1 of the drawing. The bracket 7 is secured to one end of the machine casing and supports the flue 8 which has communication with the interior of the casing for circulation of air. This flue is adapted to be closed by means of the damper 9 fixed upon the shaft 10

which is rotatably mounted in the flue and in an upwardly extending arm of the bracket portion 7. Fixed upon the shaft 10 is the lever arm 11 which has an upwardly extending portion adapted to be engaged by one of the operating parts for automatically closing the damper as will be later explained. The lever arm has also a downwardly extending portion which has secured thereto one end of the spring 12, the other end of which is anchored to the bracket 7 for the purpose of normally maintaining the damper 9 in open position. The depending portion of the lever arm 11 is adapted to strike the stop portion 13 so as to limit the movement thereof.

The means for automatically closing the machine door and the damper includes a fusible link 14 having overlying metallic plate members 15 provided at their ends 75 with the openings 16. A fusible portion 17, as for instance solder or the like, is inserted in registering openings in the overlying portions of the plate members 15 so as to maintain the plate members together under normal conditions. The fusible link is connected at the openings 16 to the clevis members 18^a which in turn are connected to the rods 18. The brackets 19 are supported from the wall of the container and serve as 80 a means of guiding the rods 18 in their movement. The brackets 19 serve also as abutments for one end of the springs 20, the other ends of which abut the collars 21 fixed upon the rods 18. When the fusible link is 90 intact, that is under normal conditions, the springs 20 are held under tension and during this time the parts occupy the position indicated in Fig. 3 of the drawings. Each of the rods 18 is provided with a cam member 22 fixed thereupon for cooperative engagement with the nose on the lower end of the depending stem 23 which extends up through the casing and is adapted to be moved upwardly by action of the cam 22 100 when released by melting of the fusible link. The upper end of the rod 23 in each case is screwed into the clevis member 24 which has a pin and slot connection 25 with the lever arm 26 which in turn is pivoted at the point 27 upon the base portion of the rest 6. The other end portion 28 of the lever 26 overlies and is adapted to engage the free end portion of the lever arm 29 which is fixed in each case upon the shaft 30 which in turn 110

is rockably mounted within the base portion of the rest 6. The springs 31 tend to normally rotate the lever arms 29 in a clockwise direction and are seated within suitably formed recesses in the base portions of the rests 6.

Fixedly mounted upon the rock shaft 30 I have provided the door closing arms 32 which when actuated are adapted to strike the door 4 so as to force the same beyond the vertical dead center and permit the same to close by gravity.

One of the rods 18 extends out through an end wall of the container casing, as illustrated in Fig. 7, and has its end bevelled so as to engage with a cam action the upwardly extending portion of the lever arm 11 so as to rotate the shaft 10 and close the damper 9 against the tension of the spring 12, that is when the rods 18 are released upon melting of the fuse.

As before stated, when the fuse is intact the parts occupy the position illustrated in Fig. 3 of the drawings and the door 4 may rest in open position as indicated in Fig. 1. In case of fire however, the fusible portion 17 will be melted and the rods 18 will be released to the action of the springs 20 which force them outwardly to cause engagement of the cams 22 with the lower ends of the stems 23 and thereby effect rotary movement of lever arms 28 and 29 and in this way cause the arms 32 to engage the door for closing the same. At the same time one of the rods 18 as it is moved outwardly engages the lever arm 11 and causes the damper 9 to be closed in the manner just described.

In case fire should occur when the door 4 is closed, the operation of the parts just now described will cause the damper 9 to be automatically closed. In either case the fire will be prevented from spreading beyond the confines of the washing machine casing; and furthermore the fire will be smothered by automatically closing the container against ingress of air.

What I claim is:

1. In a machine of the character described, the combination of a casing having an opening, a door for said opening, and thermally controlled means including a heat responsive member located inside of said casing for automatically closing said door upon subjecting said heat responsive member to a predetermined amount of heat, said door being normally capable of being moved to both open and closed position without disturbing said thermally controlled means.

2. In a machine of the character described, the combination of a casing having an opening, a door for said opening, a work receiving container mounted within said casing, and thermally controlled means including a heat responsive member located

inside of said casing and outside of said container for automatically closing said door upon subjecting said heat responsive member to a predetermined amount of heat.

3. In a machine of the character described, the combination of a casing having an opening, a door for said opening, and thermally controlled means including a heat responsive member located inside of said casing, and a cam member for automatically closing said door upon subjecting said heat responsive member to a predetermined amount of heat.

4. In a machine of the character described, the combination of a casing having an opening, a door for said opening, and thermally controlled means including a heat responsive member and a cam member both located inside of said casing for automatically closing said door upon subjecting said heat responsive member to a predetermined amount of heat.

5. In a machine of the character described, the combination of a casing having an opening, a door for said opening, and thermally controlled means including a heat responsive member and a spring actuated cam member for automatically closing said door upon subjecting said heat responsive member to a predetermined amount of heat.

6. In a machine of the character described, the combination of a casing having an opening, a door for said opening, and thermally controlled means including opposed cam members connected by a heat responsive member for automatically closing said door upon subjecting said heat responsive member to a predetermined amount of heat.

7. In a machine of the character described, the combination of a casing having an opening, a door for said opening, and thermally controlled means including opposed cam members connected by a heat responsive member for automatically closing said door upon subjecting said heat responsive member to a predetermined amount of heat, said cam members and said heat responsive member being located within said casing.

8. In a machine of the character described, the combination of a casing having an opening, a door for said opening, means adapted when released to effect the closing of said door and including a spring actuated cam member, and a heat responsive member for controlling the release of said means, whereby said door will be closed upon subjecting said heat responsive member to a predetermined amount of heat.

9. In a machine of the character described, the combination of a casing having an opening, a door for said opening, means adapted when released to effect the closing of said door and including a spring actuated cam

member and a heat responsive member located within said casing for controlling the release of said means, whereby said door will be automatically closed upon subjecting said 5 heat responsive member to a predetermined amount of heat.

10. In a machine of the character described, the combination of a casing having an opening, a door for said opening, a conduit for said casing, a damper for said conduit, and thermally controlled means for automatically closing said door and said damper upon subjecting said heat responsive member to a predetermined amount of heat.

15. 11. In a machine of the character described, the combination of a casing having an opening, a door for said opening, a conduit for said casing, a damper for said conduit, and thermally controlled means including a heat responsive member located within said casing for automatically closing said door and actuating said damper upon subjecting said heat responsive member to a predetermined amount of heat.

25. 12. In a machine of the character described, the combination of a casing having an opening, a door for said opening, means adapted when actuated to close said door, a conduit for said casing, a damper for said 30 conduit, means adapted when actuated to close said damper, a single member for actuating said door closing means and said damper closing means, and a member responsive to an abnormal rise in temperature for 35 controlling the operation of said single member.

13. In a machine of the character described, the combination of a casing having

an opening, a door for said opening, means adapted when actuated to close said door, a 40 conduit for said casing, a damper for said conduit, means adapted when actuated to close said damper, a single member for actuating said door closing means and said damper closing means, and a member arranged 45 within said casing and responsive to an abnormal rise in temperature for controlling the operation of said single member.

14. In a machine of the character described, the combination of a casing having an opening, a door for said opening, means adapted when actuated to close said door, a conduit for said casing, a damper for said conduit, means adapted when actuated to close said damper, a single spring actuated 50 member adapted when released to actuate said door closing means and said damper closing means, and a member responsive to an abnormal rise in temperature for releasing 55 said single member.

15. In a machine of the character described, the combination of a casing having an opening, a door for said opening, means adapted when actuated to close said door, a conduit for said casing, a damper for said 60 conduit, means adapted when actuated to close said damper, a single spring actuated member adapted when released to actuate said door closing means and said damper closing means, and a member arranged in 65 said casing and responsive to an abnormal rise in temperature for releasing said single member.

In testimony whereof I hereby affix my signature.

HOWARD C. CURTISS.
